METHOD AND APPARATUS FOR MOUNTING FILAMENTS

Original Filed May 7, 1927

INVENTOR:
Roscoe G. Phelps,
BY Alexander S. Jones
His ATTORNEY.

UNITED STATES PATENT OFFICE

ROSCOE G. PHELPS, OF CLEVELAND, OHIO, ASSIGNOR TO GENERAL ELECTRIC COMPANY,
A CORPORATION OF NEW YORK

METHOD AND APPARATUS FOR MOUNTING FILAMENTS

Original application filed May 7, 1927, Serial No. 189,514. Divided and this application filed June 9, 1927.
Serial No. 197,568.

My invention relates to electric incandescent lamps and similar articles comprising a filament sealed in a bulb or other container. More particularly my invention relates to methods and apparatus for mounting the filament on the stem which is sealed into the bulb or other container. The object of my invention is to definitely dispose the filament with reference to a portion of the stem. This has a distinct advantage in the production of devices in which the filament is definitely located with reference to the base of the device.

The present application is a division of my application Serial No. 189,514, filed May 7, 1927, and the present invention is particularly adapted for use in combination with the sealing-in method which is part of the subject matter thereof. Further features and advantages of my invention will appear from the following description of a species thereof.

In the drawing, Fig. 1 is a perspective view of an apparatus for mounting filaments; Fig. 2 is a fragmentary vertical section; and Fig. 3 is an elevation partially in section of a sealing head.

In Fig. 1 is shown a mounting device which may be conveniently located adjacent to a sealing-in machine for the purpose of accurately attaching and aligning filaments upon lamp stems prior to sealing the said stems into lamp bulbs. These lamp stems, as shown, are preferably of the tipless type such as disclosed in Mitchell and White Patent 1,428,956, and comprise a flare tube 10, an exhaust tube 11 and filament supporting and conducting wires 12-13 sealed in and extending from the flattened glass portion of the stem 14. This tipless stem assembly ready for the filament is placed upon a swivel arm 15 so constructed that the lower end of the flare tube 16 seats upon and the exhaust tube extends through a tubular mount pin 17, which is substantially like mount pins carried by the sealing-in machine, hereinafter described. In order to firmly support and align the stem upon the mounting device, I provide a clamp 18 which causes the exhaust tube to engage a groove in a block 18' aligned with the opening in mount pin 17. The in-

sertion of the stem in the swivel arm 15 may be made at any convenient position of the latter but, for the mounting of the filament, the arm 15, is caused to rest upon a stop 19. A slideable cutting block 20 is properly positioned on the base 21 to receive the projecting ends of the filament support wires 12-13 in shallow grooves 22 formed therein. After the positioning, a knife 23 is actuated to trim off ends projecting over the edge of the block 20, said knife being pivotally mounted at 24 and operated through a handle 25. The block 20 is then replaced by a pair of electrical conducting blocks 26-27 insulated from each other and partially grooved to receive the ends of the filament support wires. Mounted adjacent to the blocks 26-27 are a pair of electrical contact members 28-29 connected to a source of electrical energy. The terminal ends of a filament 30 are placed upon the ends of support wires 12-13 and the contact members brought into engagement with the contacting ends to fuse them together. The swivel arm 15 is then rotated to the vertical position against a stop 31 and by hand the filament is adjusted to the desired symmetry about the lower point of an aligning pin 32 which lies in the principal axis through the tubular member 17. The mount thus completed is then transferred from the mounting device to a machine for sealing it into a bulb.

In Fig. 3 the mount is shown inserted in a sealing machine head such as disclosed in the patent application hereinbefore referred to. It comprises a partially closed ring 33 supported upon a pair of posts 34 extending from a turret 35. The said ring is suitably shaped to receive and support a bulb 36 having its neck 37 depending over the mount pin 38, similar to mount pin 17, upon which rests the flared stem tube 10 and the exhaust tube 11 extends through mount pin 38 and is accurately positioned by reason of the fact that its lower end is held in the slotted end of a tubular pin 39. The flame for the sealing operation is applied through burners 40-41.

What I claim as new and desire to secure by Letters Patent of the United States, is:

1. In an apparatus of the class described,

the combination of an arm having thereon means for receiving and definitely positioning a stem having leading-in conductors sealed therein and projecting therefrom, a stop for holding said arm in a generally horizontal position, a trimming means comprising a block adapted to be positioned to receive the projecting ends of said conductors, a cutter operatively disposed relatively there-
5 to, a block for receiving and positioning said filament and ends and means for uniting said filament to said ends.

2. In an apparatus of the class described, the combination of a pivoted arm having thereon means for receiving and definitely positioning a stem having leading-in conductors sealed therein and projecting therefrom, a stop for holding said arm in a generally horizontal position, a trimming means comprising a block adapted to be positioned to receive the projecting ends of said conductors and a cutter operatively disposed relatively thereto, a block for receiving and positioning said filament and ends, means
15 for uniting said filament to said ends, a stop disposed so as to locate said arm in a vertical position and an aligning means whereby said filament may be symmetrically disposed relatively to the axis of said stem.

20 30 In witness whereof, I have hereunto set my hand this 6th day of June, 1927.

ROSCOE G. PHELPS.
